UNITED STATES PATENT OFFICE

2,444,195

BOOT DRYING APPARATUS

George F. Gruver, Little Rock, Ark.

Application February 5, 1947, Serial No. 726,689

1 Claim. (Cl. 34—104)

1

This invention relates to boot drying apparatus and has for its primary object to circulate warm air through hunting or fishing boots or the like for absorbing any moisture contained therein or adhering thereto.

Another object is to preserve the material from which the boots may be made by avoiding overheating of the boot material and at the same time prepare a wet boot for service.

The above and other objects may be attained by employing this invention which embodies among its features a vertically disposed stack, a boot supporting rack fixed to the stack in spaced relation to its upper end and means connected with the lower end of the stack to direct warm air through the stack and into the boot supported on said rack.

Other features include means rapidly to circulate warmed air through the boot in sufficient volume to absorb any moisture contained in the boot or boots subjected to the treatment.

In the drawings:

Figure 1 is a plan view of a boot dryer embodying the features of this invention.

Figure 2 is an end view of the dryer illustrated in Figure 1.

Figure 3 is a horizontal view taken substantially along the line 3—3 of Figure 2.

Figure 4 is a vertical sectional view taken substantially along the line 4—4 of Figure 1, showing the stacks removed.

Figure 5 is a view similar to Figure 4 taken substantially along the line 5—5 of Figure 1.

Figure 6 is a fragmentary side view of the housing illustrating the drive motor for the fan and its support.

Figure 7 is an enlarged fragmentary view illustrating the details of the stack and its connection to the housing, and

Figure 8 is a perspective view of one of the boot racks.

Referring to the drawings in detail my improved boot drying apparatus comprises a base designated generally 10 formed of a bottom plate 11 of substantially square form and having upwardly and inwardly inclined side and end walls 12 joining a top wall 13 to form a hollow frusto-pyramidal housing. The top wall 13 is provided with equally spaced circular openings 14 in which suitable discharge nipples 15 are attached in any conventional manner. These discharge nipples extend upwardly in spaced parallel relation and their upper ends are crimped as at 16 to aid in coupling the stacks, to be more fully hereinafter described, with the nipples. Formed in one of

the side walls 12 of the base or housing 10 is a relatively large air inlet opening 17 in which is fixed in any conventional manner an outwardly extending tubular collar 18 which terminates at its outer end in an out turned bead 19 for a purpose to be more fully hereinafter explained. Formed in an adjacent side wall 12 of the base or housing 10 is an opening 20 of somewhat smaller diameter than the opening 17, and welded or otherwise fixed in said opening and extending through it is a sleeve 21. The axis of the sleeve as illustrated in the drawings lies parallel with the bottom 11 as will be readily understood upon reference to the drawings. As illustrated in Figure 4 the axis of the collar 18 also lies parallel with the bottom 11 and in a plane with the axis of the sleeve 21 so that the axes intersect at a point within the base or housing 10.

Fitted into the sleeve 21 is a conventional lamp socket 22 to which a conventional flexible cord 23 containing electrical conductors is connected in a conventional manner, and screwed into the inner end of the socket 21 is a conventional heating coil 24, the free end of which projects inwardly to lie in the path of an air blast entering the base or housing 10 through the collar 18.

Clamped around the outer end of the collar 18 adjacent the bead 19 is a clamp ring 25 carrying at diametrically opposite points spaced parallel arms 26 which are connected by suitable screws 27 to the housing of a conventional electric motor 28, the drive shaft of which aligns axially with the longitudinal axis of the collar 18. Secured to one end of the drive shaft of the motor 28 and operable adjacent the outer end of the collar 18 is a fan 29 so proportioned and designed that when the motor is set into operation a draught of air will enter the base or housing 10 through the collar 18, to impinge against the heater 24. The motor 28 is coupled through the medium of a flexible cable 30 in a conventional manner so that when power is supplied to the cable 30, the motor will be driven.

Fitted over the upper crimped end of each nipple 15 is a tubular stack 31 to the upper end of which is riveted as at 32 a boot rack designated generally 33. Each boot rack 33 above referred to comprises a perforated plate 34 formed at spaced intervals with upwardly extending ribs 35, and formed between the ribs are spaced air discharge openings 36. As illustrated in Figure 8 the ribs 35 extend transversely of the plate 34, and formed on opposite side edges of the plate 34 are downturned flanges 37 which are provided

with openings 38 for the reception of the rivets 32 previously referred to.

Each stack 31 is provided intermediate its ends with aligning openings 39 for the reception of a shaft 40 carrying a damper 41 by means of which the flow of warm air through its respective stack may be regulated. One end of each shaft 40 is formed with a hand crank 42 by which the shaft may be rotated and attached to the stack adjacent the hand crank is a spring tongue 43 having notches therein for engagement with the hand crank 42 to hold it in various adjusted positions about the axis of the shaft 40 so as to retain the damper 41 in the position required.

Attached as at 44 to each stack near its lower end is the apex of a V-shaped bracket or strut 45 and the divergent ends of the arms of each bracket are fixed as at 46 to adjacent sides 12 of the base or housing 10. It will thus be seen that the stacks 31 are held in proper vertical position above the base or housing 10 and in alignment with the nipples 15.

As illustrated in Figure 2 one pair of stacks 31 is preferably of less length than the opposite pair of stacks so as to accommodate boots of different lengths. In use the boots to be dried are placed over the stacks as indicated by the broken lines in Figure 2 and upon coupling the conductors of the cables 23 and 30 to a suitable source of power supply it will be obvious that the heater 24 will be energized and the motor 28 will drive the fan 29 to cause air to be inducted into the interior of the base or housing 10 from whence it will flow upwardly through the nipples 15, stacks 31 and thence into the boots seated on the boot racks 33. Due to the spacing of the plates 34 forming the bottoms of the boot racks from the upper ends of the stacks 31 it will be obvious that the warm air will flow outwardly from all sides of the upper ends of the stacks and also will be discharged through the openings 36 in the boot racks 33. In this way warm air will be circulated throughout the entire interior of each boot and eventually will find its way downwardly through the open lower end of each boot to be discharged to atmosphere. The heating capacity of the electric heater 24 will be such as to avoid overheating the air introduced into the device by the fan

29 and hence no injurious effects on the material from which the boots are made need be experienced.

While in the foregoing there has been shown and described the preferred embodiment of this invention it is to be understood that minor changes in the details of construction, combination and arrangement of parts may be resorted to without departing from the spirit and scope of the invention as claimed.

What I claim is:

Boot drying apparatus which includes a hollow frusto-pyramidal housing, a plurality of air discharge nipples communicating with the interior of and extending upwardly from the housing, said housing having an inlet opening in one side wall, a fan mounted on the housing for directing air into the housing through the opening, said housing having a second opening in a side wall adjacent that having the air inlet opening therein, a collar fitted in the second opening, an electrical heater entering the housing through the collar and disposed in the path of the air introduced into the housing by the fan, a stack extending upwardly from each nipple, a boot rack fixed to each stack in spaced relation to its upper end, a damper in each stack to regulate the flow of air upwardly therethrough, each boot rack having spaced rows of perforations extending therethrough and transverse ribs extending upwardly from each boot rack in spaced parallel relation to the rows of perforations.

GEORGE F. GRUVER.
